UNITED STATES PATENT OFFICE.

PAUL G. SWARS, OF PITTSBURGH, PENNSYLVANIA, ASSIGNOR TO WESTINGHOUSE ELECTRIC & MANUFACTURING COMPANY, A CORPORATION OF PENNSYLVANIA.

CROSSING FOR TROLLEY CONDUCTORS.

Application filed October 29, 1925. Serial No. 65,636.

My invention relates to overhead equipment for electric railways, and particularly to crossings for trolley conductors.

One object of my invention is to provide a device of the above-indicated character that shall be simple and durable in construction, economical to manufacture and erect, and effective in operation.

Another object of my invention is to provide a cross-over that will hold trolley conductors in a fixed relation to each other at the point where they cross and keep them from rubbing against each other.

Another object is to provide a good electrical path between the trolley conductors, in order to prevent harmful arcing.

It is also an object of my invention to reduce the number of parts, and at the same time provide means for keeping the crossing from buckling.

In practicing my invention, I provide a crossing with a body member having channels adapted to receive and hold the respective trolley conductors. The body member is provided with an aperture in its center, and located therein is a center-piece having grooves in its top portion to receive the trolley conductors and a lug on its lower end to guide the trolley wheel. The center-piece also acts as a compression block and prevents the body member from becoming distorted when under strain caused by the tension of the trolley conductors.

My invention will be more readily understood by reference to the accompanying drawings, in which

Figure 1 is a plan view of a crossing embodying my invention.

Fig. 2 is a view, partially in section and partially in side elevation, of the crossing shown in Fig. 1.

Fig. 3 is a perspective view of the center-piece of the crossing.

Referring to the drawings, the structure therein shown comprises a crossing having a body member 1 that is provided with two pairs of channels 2, which are located on the top side of the crossing and are adapted to receive transversely disposed trolley conductors 3. The body member 1 is provided with two pairs of arms 4 that extend along the trolley conductors 3 and hold them in operative position. The arms or extended portions 4 may be so constructed that they will firmly grip the trolley conductors, or

they may be constructed to receive a trolley conductor approach member 5, of bayonet form, such as is illustrated in my copending application, Serial No. 632,183, filed April 16, 1923, allowed May 8, 1925.

The body member 1 is also provided with an aperture 6 in its center, and an annular shoulder 7 is located in the walls of the aperture parallel to the plane of the crossing, the aperture and shoulder being adapted to receive and hold a center-piece or compression block 8, as clearly shown in Fig. 2.

The upper part of the center-piece 8 is provided with channels 9 and 10 in its sides in different planes and at right angles to each other. The lower part of the center-piece 8 is extended in the form of a rounded lug 11 to act as a center guide for current collectors. The extension of the lug 11 also forms a ledge 12 on the center-piece 8 which is adapted to rest against the shoulder 7 in the aperture 6 in the body member 1 when the center-piece 8 is in operative position.

The body member 1 of the crossing is also provided with upwardly extending symmetrically disposed ribs 13, which are angular in form and are located near its center to help define the trolley conductor channels 2.

The center-piece 8 is of approximately rectangular shape and is made large enough to practically fill the upper part of the aperture 6 in the body member 1, in order that it may act as a base or compression block against the corners of which parts of the ribs 13 will strike and rest and thereby prevent buckling or distortion of the crossing when it is placed under strain by reason of the tension of the trolley conductors 3.

The body member 1 of the crossing is also provided with eyelets 14 through which supporting wires may be fastened to hold the crossing in place after it is erected.

The body member 1 is preferably further provided with ridges 15 on its bottom side that are adapted to guide current collectors as they pass along under the crossing.

When it is desired to erect the crossing, the trolley conductors 3 are placed in position across each other and the center-piece 8 is placed at the crossing point so that one of the trolley conductors lies in the groove 9 and the other in the groove 10. The body member 1 of the crossing is then pressed

upwardly against the trolley conductors 3 so that they will lie in the trolley conductor channels 2 and the center-piece 8 enters and is located in the center aperture 6 of the body member 1. While the body member is being held in this position, the bayonet approach members 5 are placed on the trolley conductors 3 and driven home into the outer ends of the arms 4 of the crossing, so that the trolley conductors 3 are firmly gripped and held in operative position.

The trolley conductors 3 will then be held firmly in a fixed position with relation to each other by the center-piece 8 at the point 15 where they cross, and inasmuch as each trolley conductor lies in its own channel, it will be prevented from rubbing or chafing against the other trolley conductor. The placing of the trolley conductors 3 in the 20 grooves 9 and 10 will also cause them to retain the center-piece 8 in the aperture 6, after the crossing is erected. Furthermore, the center-piece 8 has such a large area of intimate contact with each trolley conductor 25 at and near the crossing point that a good electrical connection between the conductors is provided and arcing is prevented.

If the lug 11 on the center-piece 8, which acts as a center guide for the current collectors, becomes worn, the center-piece may be removed easily and be replaced by a new one.

I have shown the center-piece or compression block 8 as being substantially rectangular in form and the body member 1 as being in one piece, but it may be advisable to make the body member 1 of two pieces with an annular aperture 6 in the center and provide a center piece of cylindrical form, in order 40 that the crossing may be adjusted to suit any angle at which the trolley conductors cross each other.

While I have shown and described a particular form of my invention, I desire it to 45 be understood that changes may be effected therein without departing from its spirit and scope as set forth in the appended claims.

I claim as my invention:

50 1. A crossing for trolley conductors comprising a body member provided with channels for the conductors and having an aperture in its center, and a grooved center-piece located in the aperture to cooperate with the body member in holding the conductors.

2. A crossing for trolley conductors comprising a body member provided with channels for the conductors and having an aperture in its center, and a center-piece located 60 in the aperture and provided with grooves in its upper portion to hold the conductors and having a lug on its lower portion adapted to guide a current collector.

3. A crossing for trolley conductors comprising a body member provided with channels for the conductors and having an aperture in its center within which is located a shoulder, and a grooved center-piece provided with a ledge adapted to rest on the shoulder and located in the aperture to co- 70 operate with the body member in holding the conductors.

4. A crossing for trolley conductors comprising a body member provided with channels for the conductors and having an aperture in its center, and a center-piece provided with a groove for each conductor and located in the aperture to cooperate with the body member in holding the conductors.

5. A crossing for trolley conductors comprising a body member provided with channels for the conductors and having an aperture in its center within which is located a shoulder, and a grooved center-piece provided with a ledge adapted to rest on the shoulder and located in the aperture to co- 80 operate with the body member in holding the conductors and having a lug on its lower portion adapted to guide a current collector.

6. A crossing for trolley conductors comprising a body member provided with channels for the conductors and having an aperture in its center, and a center-piece located in the aperture and having grooves in its upper portion placed at an angle to each 90 other for receiving the conductors and maintaining them in fixed relation to each other.

7. A crossing for trolley conductors comprising a body member provided with channels for the conductors and having an aperture in its center, and a compression block located in the aperture to keep the body member from buckling.

8. A crossing for trolley conductors comprising a body member provided with channels for the conductors and having an aperture in its center, and a center-piece provided with grooves for receiving the trolley conductors and keeping them in fixed relation to each other and having a lug on its lower end adapted to guide a current collector and act as a compression block to keep the body member from buckling when under strain.

9. A center-piece for trolley conductor crossings having grooves in its upper portion for receiving the conductors and a lug on its lower portion for guiding a current collector.

10. A center-piece for trolley conductor crossings provided with grooves in its upper portion for receiving the conductors.

In testimony whereof, I have hereunto subscribed my name this 23rd day of October 1925.

PAUL G. SWARS.
